UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

TABULATING MECHANISM FOR ADDING MACHINES.

Application filed October 14, 1921. Serial No. 507,613.

To all whom it may concern:

Be it known that I, FRANK C. RINSCHE, a citizen of the United States, residing at Detroit, in the county of Wayne and State of Michigan, have invented certain new and useful Improvements in Tabulating Mechanisms for Adding Machines, of which the following is a specification.

The present invention relates to cross-
10 tabulating equipments for adding and listing or like machines and the principal object is to provide improved means for controlling the movement of a laterally shift-
able paper carriage in the performance of
15 tabulation work to enable the operator more conveniently and expeditiously to vary the normal order of tabulation to suit the particular accountant work to be accomplished.

The invention in the illustrative form of
20 embodiment herein described and shown is applied to the well known Burroughs machine. I am aware that there are numerous patents exemplifying various forms and arrangements of tabulating mechanisms applied to this, as well as to other types of adding machines and adapted to perform various sorts of tabulation work. It may be helpful in this connection to refer specifically to several prior patents which will
25 serve in a general way to indicate the state of the art. Patent No. 977,582, issued December 6, 1910, upon an invention of Edward R. Barrett, and Patent No. 1,046,
30 546, issued December 10, 1912, upon an invention of Russell E. Benner, show tabulating equipments which provide for columnar shift of the carriage from right to left in an automatic manner from one columnar position to the next and also provide for
35 automatically returning the carriage in the opposite direction to its first columnar position as an incident to the operation of the machine with the carriage in its last columnar position. Patents Nos. 1,063,181 and
40 1,135,500, issued June 3, 1913, and April 13, 1915, respectively, upon inventions of John J. Chapin, and Patent No. 1,172,485, issued February 22, 1916, upon an invention of mine disclose tabulating arrangements providing means for shifting the paper carriage from any columnar position to any other columnar position at the will of the operator without regard to any regular order or succession of columns, the shifting

of the carriage being automatic in the 55 Chapin patents under the control of the tabulating keys, and the shifting in the patent granted on my invention being accomplished by a manually operable lever when the usual column stops or dogs are dispensed 60 with.

The present invention aims to take care of a somewhat different sort of tabulation in which items or amounts may ordinarily be printed in the same horizontal line in all 65 columns of the paper or work sheet and which occasionally requires that the last item or amount in a horizontal line be printed in an intermediate column and that the first item or amount of the next line be printed 70 in a different intermediate column and also in some cases does not require printing of items in an intermediate column or columns. In the preferred form of embodiment of the invention disclosed herein, the machine is 75 particularly adapted to perform certain classes of bookkeeping work but for the sake of clearness and illustration it has been shown and described as peculiarly adapted to make out monthly bank statements, such 80 as those usually furnished to depositors. In such class of work it is usually desirable to print the old balance in the first column (left hand) on the statement, the amounts of several checks cashed by the bank in the next 85 columns appropriated for that purpose, the amount deposited in the next column, and the new balance in the last column. It will sometimes happen that fewer checks have been cashed than there are check columns 90 provided for or that no checks have been cashed, in which event it is preferable to move the carriage directly to the deposit columnar position upon operation of the machine to print the amount of the last 95 check or to print the old balance in the first column, thus eliminating or dispensing with blank operations of the machine with the carriage in the intermediate check columnar position or positions. In some cases there 100 may be more checks cashed than there are check columns provided for and then it is desirable to record the amounts of the additional checks in the check columns on the next horizontal line and omit recording in 105 the deposit and new balance columns at the end of the first printed line of checks and also the recording of the old balance in the

first column of the second printed line of checks. To take care of this sort of tabulation the laterally shiftable carriage of the machine, embodying the present invention, is normally and automatically moved by the carriage spring from right to left from one columnar position to the next to effect the printing of items and amounts in all the columns on the statement sheet. Upon operation of the machine with the carriage in the "new balance" or last columnar position, a clutch, intermediate a motor and the carriage, is rendered effective and the motor returns the carriage to the right to its "old balance" or first columnar position. In order to effect continuous movement of the carriage directly from the "old balance" position or one of the check positions to the deposit column without stopping the carriage at an intermediate check columnar position or positions a key or touch bar (herein called the "deposit" key) and connections are provided so that when the machine is given an operation upon depression of the key the column stop fingers or dogs are moved to ineffective position during movement of the carriage past the intermediate check columns, the carriage being arrested in deposit columnar position. A manually depressible key (called the "check" key herein) is provided for effecting return movement of the carriage directly to the first check columnar position after an amount has been printed in the last check column connections being operated by the key to render the clutch effective and to position a device for rendering the clutch ineffective at the proper time to position the carriage in the first check columnar position without the necessity of operating the machine proper.

With the above and incidental objects in view the invention consists in certain novel features of construction and combinations of parts the essential elements whereof are recited in the appended claims, and the preferred form of embodiment of which is described in detail hereinafter and illustrated in full in the accompanying drawings which form part of this specification.

Of said drawings, Fig. 1 represents an adding machine of the well-known Burroughs type, having applied thereto a tabulating mechanism embodying the present invention, the machine being represented in right-hand side elevation with the enclosing casing of the machine and the housing for the motor drive connections shown in section and parts of the supporting frame broken away; Fig. 2 is a left-hand side elevation of the rear portion of the machine with some of the parts broken away; Fig. 3 is a rear elevation of the machine showing in section the housing for the motor drive connections and other parts; Fig. 4 is a

top plan view of the laterally shiftable carriage with the platen and paper support or back and the top cover of the housing for the motor drive connections removed, and certain parts in section or broken away to disclose the invention more clearly to view; Fig. 5 is a vertical section taken on the line 5—5 of Fig. 3 and shows some of the parts in the positions which they assume when the carriage is in the deposit columnar position; Fig. 6 is a left hand side elevation, partly in section, of the laterally shiftable carriage showing some of the parts in the positions which they assume while the carriage is moving directly to the deposit columnar position from any one of the first three columnar positions; Fig. 7 is a fragmentary rear elevation with parts broken away showing part of the control mechanism for the carriage and illustrating the parts in the positions which they assume while the carriage is being moved by the electric motor towards the right (as viewed from the front); Fig. 8 is a front elevation of the control mechanism shown in Fig. 7 as well as other parts and illustrates the condition of the parts just as the clutch is released upon movement of the carriage slightly to the right of the first columnar position; Fig. 9 is a view similar to Fig. 8 except that some of the parts of the Fig. 8 are not shown, and illustrates the position of the parts just as the clutch is to be released when the carriage is moved directly from an advanced columnar position to the first check columnar position; Fig. 10 is a perspective view of the cam device on the carriage for effecting release of the clutch upon return of the carriage to the right; Fig. 11 is a vertical section taken on the line 11—11 of Fig. 4; Fig. 12 is a section taken on the line 12—12 of Fig. 11; Fig. 13 is a plan view of the carriage return clutch; Fig. 14 is a perspective view of the carriage return clutch showing the parts in disassembled relation; Fig. 15 is a section taken on the line 15—15 of Fig. 11; Fig. 16 is a perspective view of the yoke-shaped members operated by the check and deposit keys; Figs. 17 and 18 are perspective views of the clutching elements of the frictional drive clutch; Fig. 19 is a detail view showing the check key in depressed condition and some of the parts actuated thereby in moved position; Fig. 20 is a sectional view through the device on the carriage rack bar for rendering the carriage return clutch effective; Fig. 21 is a view of a portion of a statement showing the character and form of tabulation which a machine, embodying the present invention, is adapted to perform.

Machine proper and paper carriage.

As stated above, the invention herein shown is applied to the well-known Bur-

roughs adding and listing machine, but it is to be understood that it is not to be limited necessarily in its application thereto. It will also be apparent that the tabulating equipment, embodying the present invention, is adapted for other purposes than making out monthly bank statements and that in the present description it is described as being peculiarly adapted for making out such statements only for the purpose of illustration and for the sake of convenience and clearness.

In view of the fact that the Burroughs machine is in extensive commercial use and its basic principles of operation are well known it will be wholly unnecessary to describe the machine proper in any detail but certain familiar elements thereof will be pointed out as more intimately concerned in the carrying out of the functions of the present invention. The usual numeral keys 25 (Fig. 1) are employed for setting up the various items and controlling the extent of movement of the usual actuating levers 26 which carry the type plates for presenting the items and totals at the printing line, racks being carried by the forward end of the levers for actuating the usual adding and subtracting registers. A back panel 27 of the supporting frame work of the machine has secured to it the usual track 28 upon which the laterally shiftable carriage 29 runs. A rotating platen 30 is supported in a rocking frame 33 mounted on a cross rod 34 which is carried by the carriage. The rocking frame 33 also carries a paper support or back 32 (shown broken away in Fig. 3) for holding upright the monthly statements, such as that shown in Fig. 21, the supporting back being preferably the same as that disclosed in Patent No. 1,208,375 granted December 12, 1916, on an invention of mine, and reference may be made to such patent for a complete description of the rocking frame and devices supported thereon as well as for the manually operated line spacing mechanism.

Also mounted on the carriage is a rock shaft 35 carrying a series of column stops or dogs for determining the columnar position of the carriage. On each operation of the machine, when the carriage is to be moved from right to left from one columnar position to the next by the carriage spring 41 (Fig. 4), releasing mechanism 37 (Fig. 3) is operated by a cam 38 (Fig. 2) through a lever 39 to rock the shaft 35 and thereby move one of the stop dogs 36 out of engagement with a permanent stop 40, the shaft 35 being rocked back to normal position by its spring, so that the next stop dog abuts the permanent stop 40 to arrest the carriage in the next columnar position, all of which is the usual construction and operation in the Burroughs machine. The ma-

chine is operated by an electric motor 43 through suitable connections, the motor and connections being the same as those substantially described in the Patent No. 866,750 issued September 24, 1909, upon an invention of Jesse G. Vincent, and reference may, if desired, be had to such patent for a detail description of the same. Suffice it to state in the present specification that when the touch or finger bar 44 is depressed by the operator, a clutch is rendered effective through levers 45 and a bar 46 (Fig. 1) whereupon the drive shaft 47 is given its positive stroke by the motor through a crank arm 48, a link 49 and an arm 50, the drive shaft 47 being returned to its normal position by the customary power springs 52.

Carriage return motor connections.

As an incident to the operation of the machine when the carriage is in its last columnar position, this being the position in which the new balance is printed on the bank statement (Fig. 21), the carriage is returned to its first columnar position, in which the old balance is printed, by the motor 43 through suitable connections which will now be described. For the sake of convenience and in order to avoid repetition the movement of the carriage to the right or left will be referred to as viewed from the front of the machine and the columnar positions will be considered as being numbered from left to right, the first columnar position being the "old balance" position.

Mounted on an extension 53 of the motor case is a housing 54 (Figs. 1 and 3) in which is journaled a shaft 55 connected to the armature shaft 56 of the motor 43. A worm gear 61 meshes with a gear 58 fast on a shaft 59 which is journaled in the casing 54 and connected at its upper end by a tongue-and-groove connection to one member of a frictional clutch 57 (Fig. 11) which will be described hereinafter, the clutch being interposed between the shaft 59 and a shaft 60 which at its upper end is journaled in bearings carried by a vertical housing 63 circular in cross section and mounted on the housing 54. Carried on the upper end of the housing 63 is still another housing or casing 64 of more or less irregular contour or shape, the housing 64 being rigidly secured to the upper end of the housing by a depending split collar 72 on the housing 63 which encircles the upper cylindrical end of the housing 63 and rests on an annular shoulder 65 on the latter, the collar 72 being drawn tightly into binding engagement with the supporting portion of the housing 63 by a screw 66 (Fig. 2) projecting through ears 67 on the collar 72. Splined on the upper end of the shaft 60 is a gear 68 (Figs. 4 and 11) meshing with a gear 69 journaled on a stud 71 secured in a web 62 on the

housing 64. Mounted on the upper reduced end of the stud 71 and held against vertical movement thereon by the head of a screw 73 is a gear 74 of the same diameter as the gear 69 and meshing with a rack bar 75 mounted on the paper carriage 29. Upon normal operation of the machine and when the carriage is shifted from right to left by the carriage spring 41, the rack 75 is moved 10 with the carriage and rotates the gear 74 which is normally disconnected from the gear 69, but when the machine is operated with the carriage in the last or new balance columnar position the gears 69 and 74 are 15 automatically coupled together whereupon the gear 74 is rotated in a clockwise direction by the electric motor through the above described connections to return the carriage to its first or old balance columnar position 20 in opposition to the carriage spring.

The device for clutching the gears 69 and 74 together will now be described. A clutch member 76 (best shown in Figs. 8, 11, and 14) is positioned on an integral collar or hub 77 of the gear 74 and is provided with an annular groove 78 and two projections or wings 79 from which depend pins or studs 80. The gear 74 is provided with two arcuate slots 83 and also an annular groove 30 or depression 84 in its upper face and a corresponding groove 85 is formed in the upper face of the gear 69. The pins 80, the lower ends of which are inclined or beveled in opposite directions, project through the 35 slots 83 in the gear 74, but normally the lower ends of the studs do not project below the lower face of the gear 74 and therefore the studs are normally out of the path of movement of squared studs or projections 86 positioned in the groove 85 of the gear 69 and having their upper faces beveled or inclined in opposite directions. It will be seen that when the clutch member 76 is lowered, as an incident to the operation of 40 the machine and with the carriage in the last columnar position to print the new balance, by means to be described presently, the ends of the studs 80 are moved into the path of movement of the studs 86 on the gear 69 which is continuously rotated in an anti-clockwise direction by the motor through the above described motor drive connections. Immediately upon contact of 45 the studs 86 with the studs 80 the clutch member 76 is moved relatively to the gear 74 against the tension of a spring 88 connected to studs on the gear 74 and the clutch member 76, and after the studs 80 have been carried into engagement with the ends of the 50 slots 83 towards which they are moving, the gear 74 is moved with the gear 69 to return the carriage to its first or old-balance columnar position.

The lower ends of the studs 80 and the 55 upper faces of the studs 86 are beveled or

inclined in the same directions so that if these ends come into contact when the clutch member 76 is lowered, the studs 80 will not bind on the studs 86. If the ends of the studs 80 and 86 were horizontal, instead of 70 beveled, there would be danger of the ends abutting each other and preventing the clutch member 76 from being lowered. But even with the lower and upper faces of these respective studs beveled, there is a possibility of the inclined or beveled faces of the studs 80 striking or binding on the beveled faces of the studs 86. The spring 88 is employed to prevent a misoperation of the clutch, should the studs tend to bind as just 75 stated, it being evident that if they bind they will move together thereby placing the spring 88 under tension so that the latter tends to restrain movement of the clutch member 76 (the tension of the spring 88 80 being insufficient to effect movement of the carriage) thus breaking the binding joint between the studs to permit the lower faces of the studs 80 to ride down the beveled faces of the studs 86 and then the studs 80 90 are picked up by the respective studs 86 during the next half rotation of the gear 69. The spring 88 also performs the function of partially absorbing the initial load or shock due to the sudden movement of the 95 carriage towards the right from a position of rest.

Means for closing carriage return clutch.

Near the end of the operation of the machine to print a total with the carriage in the last columnar position, the total printed being the new balance, the shaft 35 is rocked as usual, whereupon the appropriate column dog 36 is moved out of engagement with the 100 permanent stop 40 and the carriage is moved slightly past the last columnar position toward the left to operate the following described connections for closing the carriage return clutch, described above. The rack 75 105 is provided with studs 89 (Figs. 3 and 7) projecting through elongated slots 90 in laterally extending projections 93 on plates 94 secured to the end plates of the paper carriage. A spring 95 is connected at its ends to studs on the rack 75 and the extension 90 on the right-hand plate 94 (as viewed in Fig. 3) and normally serves to maintain the rack in the position, relative to the carriage, shown in Fig. 3. A block 96 (Figs. 3, 4, 7 110 and 20) is slidably mounted on the rack bar 75, the block being provided in its lower face with the T-shaped slot in which fits a track 97 integral with the rack bar. Secured to this block 96 is a cam or clutch throw-in 115 finger 297 which, when the carriage is moved to the left slightly past the last columnar position near the end of the operation of the machine as above stated, engages a stud 98 (Fig. 7) on a lever 99 and rocks the latter 120 125 130

about its pivot 100 whereupon a stud or roller 103 (Figs. 8 and 9) on one end of the lever 99 lowers the clutch member 76 into clutching position as above described, the roller 103 being positioned in the annular groove 78 of the clutch member 76. The carriage return clutch now being effective, it is apparent that the carriage will be moved toward the right to its first columnar position in opposition to the carriage spring 41. The lever 99 is pivoted to a plate 104 fast to a plate or web 105 integral with the gear housing 64. The lever 99 is shown in Fig. 7 in its rocked position and the finger 297 is shown in two positions, the position represented by the dash lines being that which the finger assumes when the clutch is closed.

During the first step or increment of movement of the rack bar 75 by the motor through the above described motor drive connections and carriage return clutch the rack bar is moved (toward the left as viewed in Figs. 3 and 7) relatively to the carriage because of the slot and stud connections 89—90, the rack bar being moved against the tension of the spring 95 relative to the carriage until the studs 89 engage the left hand ends (as viewed in Figs. 3 and 7) of the slots 90 in the projections 93, whereupon the carriage is then moved with the rack bar. The spring 95 also serves to partially absorb the initial shock or load due to the movement of the carriage from its position of rest by the motor. This initial movement of the rack bar relative to the carriage is utilized to effect line-spacing and also to disable the columnar dogs 36 during return movement of the carriage, it being obvious from the construction of the dogs that it is necessary to hold the dogs out of normal position during the return movement of the carriage to the right so that they will not engage the permanent stop 40.

45 *Disabling stop dogs during carriage return.*

The mechanism for retaining the stop dogs 36 in ineffective position during return movement of the carriage to the right is best shown in Figs. 3, 6, and 7, and will now be described. A cam plate 106, mounted on the rack bar 75, has a cam or inclined edge 107 adapted to act upon a roller 108 carried by a lateral extension 109 of a lever 110 journaled on a cross-rod 113 mounted in the plates 94 on the paper carriage. The forward end of the lever 110 is provided with a laterally extending finger 121 which projects in front of an arm 114 of a yoke-shaped member 115 loose on the cross rod 116 also carried by the carriage. Fast on the column dog shaft 35 is an arm 117 which at its upper end carries the pin 118 projecting into the slot or recess formed in

the lower end of the arm 114. From this description it will be obvious that, upon the initial movement of the rack bar relative to the paper carriage, the cam plate 106 elevates the roller 108 to the position shown in Fig. 7, whereupon the shaft 35 is rocked to the position shown in Fig. 6 through the lever 110 and the yoke 115, the stop dogs 36 being then out of operative position. The cam plate 106 retains the roller 108 in elevated position during the entire return movement of the carriage slightly past its first (old balance) columnar position and when the carriage return clutch is disabled as will now be described, the spring 95 moves the rack bar 75 back to normal position relative to the carriage, thereby moving the cam plate 106 out of cooperative relation with the roller 108 to permit a spring 119, connected to the yoke member 115 and to the carriage frame, to restore the yoke member, the shaft 35, the column dogs 36 and the lever 110 to normal positions, the carriage being arrested in its first columnar position when moved slightly back towards the left by the carriage spring after the carriage return clutch has been disabled.

Means for opening carriage return clutch.

Slidably mounted on the track 97 of the carriage rack bar is a block 120 (Figs. 3, 8 and 10) fast to one side of which is a cam finger 123 having an inclined or cam edge 124 on its outer end. When the carriage is moved toward the right by the motor slightly past its first columnar position, the inclined edge 124 engages a stud 125 on one end of the lever 99 thereby rocking the lever to raise its roller 103 and hence the clutch member 76 to disable or disconnect the carriage return clutch, the carriage then being shifted slightly toward the left by the carriage spring to its first columnar position.

The lever 99 is retained in its normal position (Figs. 3 and 4) or in its moved position (Figs. 7 and 9) by engagement of a stud 126 in the appropriate notch 127 or 131 formed in the lever 99. The stud 126 is carried by an arm 128 pivoted on the plate 104 and connected to a spring 129 which is tensioned and hence retains the pin 118 in the notch 127 when the lever is in normal position and in the notch 131 when the lever is in moved position.

Adjustability of control fingers 123 and 297.

As is customary in the Burroughs machine the column dogs 36 are adjustable on the shaft 35 to predetermine the columnar positions and hence accommodate the making out of records of various sorts and on different widths of statements or work sheets. The block 96, carrying the clutch throw-in finger 297, and the block 120, carrying the clutch

throw-out finger 123, are therefore adjustably mounted on the rack bar 75 so that they may be positioned in accordance with the positions of the first and last column dogs to enable and disable the carriage return clutch at the proper times. Pivoted in a longitudinal groove 132 (Figs. 6 and 20) in the block 96 is a lever 130 provided with a finger 133 (Fig. 20) which projects through an aperture at the bottom of the groove 132 and is adapted to engage and be held in engagement with any one of a plurality of holes 134 formed in the upper face of the track 97 on the rack bar 75, the finger 133 being maintained in the desired hole by a spring 135 compressed between the lower edge of the lever 130 and the block 96. If the carriage is given a too sudden or slamming movement toward the left (or toward the right as viewed in Figs. 3 and 7) past its normal extent of movement during the "limbering up" of the machine or by the carriage spring, an inclined edge 136 of the lever 133 will engage under a roller stud 174, to be referred to more particularly hereinafter, whereupon the lever 130 will be rocked to move its pin 133 out of its normal engagement with one of the holes 134 to permit the carriage to continue its movement toward the left independently of the block 96 and hence prevent injury or damage to the parts due to the slamming of the carriage.

The machine is "limbered up" by moving the carriage back and forth by hand in order to overcome any sluggishness or retarding tendency due to the moist condition of the machine, occasioned by atmospheric conditions, or to the oil in the bearings becoming thick or gummy while standing idle or from low temperature. During this "limbering up" operation, the tabulator stop dogs 36 are disabled by the manual rocking of the yoke-shaped handle 115, which has the downwardly extending projection 114, (Figs. 1 and 3) engaging with the stud 118 on the outwardly extending arm 117 fast on the rock shaft 35 and while the stop dogs are so disabled the carriage is shifted back and forth by hand. When the carriage is moving to the right (as viewed in Fig. 3) under control of its spring drum during a normal operation of the machine, sluggishness of the stop shaft 35 and the associated parts may prevent a stop dog 36 from returning into engagement with stop 40 with the result that the carriage might overthrow past its normal limit of movement. If the latch 130 were not provided, upon overthrow of the carriage in that direction, either during the "limbering up" operation or a normal operation of the machine, as just explained, the roller stud 174 might ride up the cam plate 297 and when the carrying plate 168

is then blocked from further vertical movement by the limiting slots 172 (Fig. 7) and 166 (Fig. 1), the roller stud 174 and associated parts might be injured, or if they did not give way, the bar 75 might be carried to the left to the limit of the slots 90 (Fig. 3) with the result that the studs 89, engaging the ends of the slots, might be torn from their fixed position. However, with the latch 130 provided, the block 96 will be released by means of the roller 174 camming one end of the latch 130 downward thus lifting its pin 133 and hence permitting the block 96 to slide along the bar 75 instead of carrying the bar with it with the possible attendant injury to the mechanism.

Pivoted to the finger 123, as best shown in Figs. 3 and 10, is a lever 138 having one end bent laterally to position an integral pin 139 in any selected hole 134 in the rack bar, the pin being held in the hole by a spring 140, compressed between the upper face of the block 120 and a lateral extension 143 on the lever 138, the lever 138 being operable to position the pin 139 in the desired hole 134 to determine the extent of return movement of the carriage to the right. If the carriage is slammed past its normal limit of movement to the right by the motor a cam finger 141 on the lever 138 rides under a stud 142, whereupon the lever 138 is rocked to disengage its pin 139 from a hole 134, thus avoiding probable injury to the finger 123 and associated parts.

Similarly, with the block 120 rigidly secured to the rack bar 75, overthrow of the carriage, toward the left as viewed in Fig. 3, either during the "limbering up" operation or under the control of the motor, might result in the cam finger 123 riding up over the top of the stud 174, when in depressed condition, with the result of either breaking the cam plate 123 or injuring the roller stud 174 or its supporting plate. Or the block 120 might strike the roller stud 142 and injure this stud or its supporting arm 217, or the roller stud 125 and its supporting arm 99. However, with the latch 138 provided, it will be seen that when the carriage overthrows toward the left (as viewed from the rear) it will necessarily release the latch and the block 120 will move along the bar instead of remaining rigid and causing breakage of the parts.

Line spacing.

It is customary in the Burroughs machine to effect the line-spacing between horizontal rows of printed amounts at each operation of the machine by the cam 38 (Fig. 2) through suitable connections, but in the present construction the line-spacing mechanism of the carriage is operated automatically as an incident to the return movement

of the carriage to the right and the step of the movement of the rack bar 75 relative to the carriage, when the carriage return clutch is rendered effective, is taken advantage of to operate this mechanism. Pivoted on the upper rear end of the lever 110 (Fig. 6) is a lever or pawl 145 which is normally held out of engagement with a ratchet wheel 146 on the roller platen by a sleeve or collar on the shaft 34. When the lever 110 is rocked counter clockwise as viewed in Fig. 6, by the cam plate 106 on the rack bar 75, as above described, a spring 147, connected to one end of the lever 145 and at its other end to the lever 110, raises the forward end of the lever 145, whereupon the nose of the pawl engages a tooth on the ratchet wheel to rotate the ratchet wheel and platen one line space. When the cam plate 106 is moved from under the roller 108, as above described, the pawl 145 is restored to the position shown in Fig. 6 upon return movement of the lever 110 to normal position.

Skipping check columns.

The description thus far given explains fully the operation of the machine when it is operated to print items or amounts in all of the columns in succession on a horizontal line, the carriage being returned automatically to the first columnar position as an incident to the operation of the machine with the carriage in its last columnar position. However, in making out bank statements and also other kinds of statements or records, which the machine embodying the present invention is adapted to perform, it often happens that it is desirable to skip a certain column or columns for the reason that there is no amount or amounts appropriate to such columns, the work then being more expeditiously and conveniently performed by avoiding or eliminating blank operations with the carriage in such columnar positions. As aforesigned, in making out bank statements, it occasionally happens that there are fewer checks cashed than there are check columns, or that there are no checks to be recorded, in which case it is desirable to skip from the column in which the last item is printed directly to the deposit column and the mechanism for controlling the operation of the machine to perform this result will now be described in detail.

A key 148 (Fig. 1), called the "deposit" key herein and positioned on the right hand side of the keyboard, is provided with a finger-piece projecting over the rear end of the familiar touch bar 44. The key 148 is pivoted to an arm 150 fast on a shaft 153 to which is also fast a rearwardly extending arm 154, the key being maintained normally in elevated position by a spring 155 connected to the arm 150 and a stud on the

frame of the machine. The arm 154 is connected through a link 156 to the forward end of the lever 157, pivoted centrally to a stud 158 on the frame of the machine. The rear end of the lever 157 carries a roller 159 which projects through a slot 160 (Fig. 16) formed in one arm of a yoke-shaped member 163 journaled on a shaft 162 on which is hinged the back panel 27. The member 163 is provided with an arm 164 which carries a pin 165 projecting through a slot 166 (Figs. 1 and 3) formed in the lower end of a link 167 which is pivoted at its upper end to a plate 168 (Figs. 3, 7, and 8) slidably mounted on the back plate 104, the plate 168 being provided with a slot 172 through which screws 169 project. The plate 168 is normally held in its elevated position, shown in full lines in Figs. 7 and 8, by means of a spring 173 so that the roller stud 174 which is mounted on the upper end of the plate, normally retains a bail 175, the cross-member 176 of which rests on the roller stud 174, in normal elevated position. The bail, which is loose on the cross rod 113, comprises the cross-bar 176 and side arms 177 (Figs. 2 and 5) provided with projections 178 which when the lever or bail is lowered as will be described presently, are adapted to contact with a square cross-rod 179 of the carriage to limit the movement of the bail. Loose on the cross-rod 113 is a lever 180 (Figs. 5 and 6), the upper curved end of which is retained in engagement with the top edge of the cross-bar 176 by a spring 183 and the bail normally holds the lower end of the lever 180 out of contact with an arm 184 fast on the shaft 35 carrying the column stops, the normal position of the lever 180, being shown in Fig. 2. When the carriage is in the first (old balance) columnar position or in the first check or second check columnar position (the second or third columnar position of the carriage) to print the old balance or the amount of a check and it is desired to print the next amount in the deposit column of the statement sheet as is the case where there are no checks to be recorded or fewer checks to be recorded than there are check columns, the deposit key 148 is depressed, the touch bar 44 being operated by the deposit key at the same time to effect operation of the machine to print the old balance or the amount of a check in the particular column in which the carriage is then positioned. Depression of the deposit key 148 through the arm 150, shaft 153, arm 154, link 156, lever 157, yoke-shaped member 163 and the link 167 lowers the plate 168 against the action of its spring 173 to the position indicated by the dash lines in Fig. 7, whereupon the spring 183 rocks the lever 180 so that the front edge of its downwardly extending arm contacts with rear edge of the arm 184,

- the bail 176 being permitted to be rocked in mal position by the spring 183 after the same direction as the supporting roller stud 174 is lowered. It is apparent that the yoke-shaped member 163 is rocked as just described because the slot 160 in its arm is inclined and the stud 159, when lowered, rides down the slot. The plate 168 is locked in lowered position by engagement of the lower end of a latch lever 186 in a notch 191 in the plate, the lever being rocked into locking position by the spring 129. The column stop shaft 35 is rocked in the usual manner whereupon the spring 183 rocks the lever 180 further in the clockwise direction to the position shown in Fig. 6 to bring its lower end over the arm 184 to prevent, until the latch lever 186 is disabled, return movement of the shaft and column dogs to normal position as will now be described.
- 20 Slidably mounted on the cross-bar of the bail 175 is a slide or plate 187, which may be adjusted and secured in adjusted position by a screw 188 (Fig. 4) manipulated by its knurled head which is provided with a stud 189. As the column dogs are held out of normal position by the lever 180, it will be apparent that the carriage spring 41 moves the paper carriage directly to its deposit-columnar position past the intermediate 30 check columnar position or positions without stoppage of the carriage in such intermediate positions and that just previous to the time the carriage reaches the deposit position but after it has moved past the third check columnar position, the stud 189 strikes the upper end of the latch lever 186 thereby swinging its lower end out of engagement with the notch 191 in the plate 163 to permit the spring 173 to raise the plate 40 and the bail 175. Elevation of the bail rocks the lever 180 in opposition to its spring 183 to move the lower end of the lever from above the arm 184, thus permitting the column stop shaft to be rocked to normal position so that the column stop, appropriate to the deposit columnar position, engages the permanent stop 40 to arrest the carriage in this latter position. The slot 166 (Fig. 1) in the lower end of the link 167 is provided to permit return of the touch bar 44, the deposit key 148 and connections to normal position upon being released by the operator, the link 167 and plate 168 being subsequently elevated to normal position upon operation of the latch 186 to release the plate 168. In order to insure movement of the lower end of the lever 180 out of contact with the foot 184 when the latch 186 is disabled, the lower portion of the slide 187 is bent around the lower edge of the cross-bar 176 of the bail 175 so that it will strike the stud 174 and rock the bail and hence the lever 180 past their normal positions to the positions shown in Fig. 5, 60 the bail and lever 180 being returned to nor-
- mal position by the spring 183 after the slide 187 has passed the stud 174.
- Listing deposits.*
- In some instances it might be desirable to list deposits, one under the other and upon successive operations of the machine, and it will be observed that, if the deposit key 148 is depressed while the carriage is in deposit columnar position, the machine is operated and the column stops are latched out of operative position in the same manner as when the machine is operated upon depression of the deposit key to move the carriage from the old-balance or the first 70 check or second check columnar positions to the deposit columnar position. Hence the carriage is moved to the left from the deposit columnar position the full extent past the last columnar position under the action 75 of its spring, the carriage return clutch being then rendered effective so that the motor returns the carriage to the first (old-balance) columnar position, but as the column stops are still held out of operative position the 80 carriage is again moved toward the left by its spring and again arrested in deposit-columnar position, the stud 189 releasing the latch 186 as the carriage approaches deposit columnar position, as before described. 85 The carriage is now in position to again print in the deposit column but on the next line, the line-spacing mechanism having been operated as an incident and preliminarily to the return of the carriage toward 90 the right.
- While the machine may be operated to list two or more deposits by depressing the deposit key 148 and allowing the carriage to complete its full travel to the left and then 95 back to the old balance position and from thence to the deposit position as just described, a more satisfactory method of listing two or more deposits may be accomplished by depressing the well known "carriage normal key" which is common to Burroughs of the present type and serves to disable the tabulating mechanism and render the line-spacing mechanism effective. 100
- If desired, listing of deposits under the control of the deposit key, as above described, may be prevented and to this end an extra slide 187^a (shown in dotted lines in Fig. 3) may be employed to arrest the carriage in the usual blank or spacing position when 105 the deposit key is operated by mistake with the carriage in the deposit columnar position, the sequence of operation being the same as when the deposit key is operated to effect movement of the carriage to the deposit columnar position from a precedent columnar position. As is well known, the spacing columnar position, which in a machine embodying the present invention is intermediate the deposit and new balance 110
- 120
- 125
- 130

columnar positions, is employed in the Burroughs machine of this type to permit a blank operation of the machine with the carriage in such position to restore certain parts of the transfer or carrying mechanism for the registers, before the total is printed, the carriage being arrested in such spacing position under the control of the columnar stop 36 appropriated thereto.

10 It is also apparent that if it is desirable to prevent the carriage from being moved directly from the spacing position or new balance columnar position to the deposit columnar position, through accidental depression of the deposit key 148, still another slide 187^b (shown in dotted lines in Fig. 3) may be provided to trip the latch 186 as the carriage moves to its new balance columnar position and to prevent the latch 186 from latching the slide 168 in depressed position should it be depressed by the deposit key when the carriage is in its new balance columnar position. When the carriage is in its new balance columnar position the 25 stud on the slide 187^b is in the position shown by the dotted-line circle, numbered 189^b in Fig. 3, so that when the bail 176 is lowered upon accidental depression of the deposit key the stud engages the left hand side of 30 the latch 186 as viewed in Fig. 3 to prevent the latch from being moved by its spring 129 into latching position and hence the carriage is stopped in its old-balance position whereas it would move on to the deposit position, 35 which is not desired.

Carriage return to first check columnar position.

When it is desired to return the carriage 40 to the first check columnar position, immediately after an amount is printed in the last check column, as is the case when there are more checks than there are check columns provided for, a special key 193 (Fig. 2), 45 called the "check" key, herein, is employed, which when depressed renders effective the carriage return clutch so that the motor returns the carriage to the right slightly past the first check columnar position whereupon 50 the clutch releasing finger 123 releases the clutch to permit the carriage-spring 41 to move the carriage slightly to the left to the first check columnar position in which it is arrested. It will be understood that when 55 the machine is operated to print an amount in the last check column on the statement sheet the carriage is moved to the deposit columnar position, and that the key 193 is then operated to effect return movement of 60 the carriage directly to the first check columnar position by the motor, the machine proper not being operated while this function is being carried out. The check key 193 is positioned at the upper left-hand side 65 of the keyboard, the key being mounted on

a stem 194 which is normally held in its elevated position with its shoulder engaging the lower keyboard plate by a spring 195, the lower end of the key stem being guided for vertical movement by a shouldered stud 70 196 engaging in the recess in the end of the key stem. Pivoted on the key stem is a latch 197, the rear edge of which is maintained in engagement with a stud 198 on the rear end of a lever 199 by a spring 200. The lever 199, which is pivoted on the stud 158, carries a stud 203 on its rear end projecting into a slot 204 provided in one arm 205 of a yoke-shaped member 206 journaled on the shaft 162 (Figs. 2, 16 and 19). A rearwardly extending arm 207 on the member 206 carries a stud 208 projecting through a slot 209 in the lower end of a link 210 pivotally supported at its upper end by a lateral extension on a plate 213 (Figs. 7, 8 and 9) which is provided with a slot 214 through which project headed screws 215, the plate 213 being slidably mounted on the plate 104 for vertical movement on the screws. The upper end of the plate 213 is bent to form a lateral projection 216 extending under the lever 99 immediately below the stud 125. Pivoted on an extension of the plate 213 is an arm 217 provided with a cam edge 218 on a projecting nose, the cam edge being normally held in engagement with the stud 125 by a spring 219 connected at its ends to studs on the plate 213 and arm 217. The upper end of the arm 217 is equipped with the stud 142 and its lower end is provided with an extension 223 adapted to limit its movement about its pivot in a clockwise direction, as viewed in Fig. 7. When the check key 193 is depressed, with the carriage in the deposit columnar position, a shoulder 224 (Fig. 2) on the latch 197, engages the pin 198 on the lever 199 to raise the rear end of the lever, whereupon the yoke member 206 is rocked forwardly, through co-action of the stud 203 and the slot 204, to raise the plate 213 through the link 210 from the position shown in Figs. 7 and 8 to that shown in Fig. 9. The plate 213 is aligned in normal position by engagement of a notch 225 in the slot in the plate with the upper stud 215 and is aligned in elevated position by engagement of a corresponding notch 226 with the upper stud 215, the plate being yieldingly held tilted slightly toward the left, as viewed in Figs. 8 and 9, by the spring 219. When the plate 213 is elevated as just described, its projection 216 rocks the lever 99 to lower the clutch member 76 and render the carriage return clutch effective so that the electric motor moves the carriage toward the right. When the clutch is rendered effective the rack bar 75 is first moved toward the right relative to the carriage to accomplish the line-spacing and to disable the column stops, as be-

fore explained. When the carriage has columnar position to another, provision is made in the form of a centrifugal governor to regulate or slightly retard the movement of the carriage and prevent any excessive impact of the column stops against the permanent stop plate 40. Referring, now to Figs. 11 and 15, this governor takes the form of a pair of weights 235, pivoted on studs 236 carried by a disc 237 secured to a hub 238 which is loose on a stub shaft 239 journaled in a bearing mounted in the cover plate 240 of the gear housing 64. Fast to the upper end of the shaft 239 is a cam plate 243 having cam edges 244 adapted to cooperate with pins 245 on the weights 235. A gear 246 on the shaft 239 meshes with a pinion 247 journaled on a stud 248 secured in the cover plate 240. A pinion 249 secured to the hub of the pinion 247 meshes with the gear 74. The pinions 247 and 249 are held on the stud 248 by a screw 251, the upper face of the gear 68 being provided with a groove 252 to accommodate the head of the screw. The governor is housed in a casing 250. When the carriage is moving to the left under impulse of its spring 41 and with the carriage return clutch ineffective, the rack bar 75 through the gear 74 and the pinions 247 and 249, rotates the pinion 246 and the cam plate 243 in the clockwise direction (as viewed in Fig. 15) and the cam plate engages the projecting ends of the studs 236 to move the disc 237 in the same direction, whereupon the free ends of the weights 235 are thrown outward by centrifugal force with their frictional faces 253 engaging the inner cylindrical face of the casing 250, thereby retarding or governing movement of the carriage to the left and lessening the impact of the column stops against the permanent stop 40. When the carriage is returned to the right by the electric motor, it will be apparent that, as the carriage return clutch has been rendered effective, the cam plate 243 is rotated through the gearing in the reverse direction, that is the anti-clockwise direction, whereupon its cam edges 253 contact with the pins 245 on the weights and rock the weights inwardly and thereby move their frictional faces 253 out of contact with the cylindrical face of the casing 250, so that the governor will not retard the return movement of the carriage by the motor.

In order to permit the slide plate 213 to be depressed by the clutch throw-out finger 123, the latch 197 (Fig. 7) is rocked by engagement of its projection 230 with a stud 233 during the last increment of depression of the check key stem 194 whereby the shoulder 224 of the latch is moved out of engagement with the pin 198 on the lever 199, as shown in Fig. 19, hence permitting return movement of the lever independently of the check key when the slide plate 213 is restored to normal position by the clutch releasing finger, as above described. If the latch 197 were not disconnected from the pin 198 and the check key held in depressed position by the operator a misoperation of the machine or breakage of the parts might occur when the plate 213 is automatically restoring to normal position.

If the check key 193 is depressed when the carriage is in the second or third check columnar position or new balance columnar position the carriage will be returned to the first check columnar position in the same manner in which the carriage is returned from the deposit columnar position to the first check columnar position, and in certain kinds of accountant work these columnar shifts of the carriage may be desirable. It is understood, of course, that the electric motor runs continuously and that when the carriage is returned directly to the first check columnar position from an advanced position the machine proper is not operated.

Carriage governor.

When the carriage is being moved toward the left by action of its spring 41 from one

120
11, 12, 17 and 18, is interposed between the shafts 59 and 60 to prevent injury to the machine in case the gearing or carriage return clutch or any of the mechanism associated with the carriage jams or fails to function 125 as intended. Removably connected to the upper end of the shaft 59 is the clutch housing comprising a base plate 255 threaded into the lower end of a cylindrical casing 256 threaded at its upper end to receive a 130

pressure regulating nut 257 held in place by a locking nut 258 and a washer. The shaft 59 is connected to the base plate 255 by a tongue and groove connection 261 between the shaft and a hub on the base plate. A circular bearing 259 on the plate 255 extends into a circular bore 260 in the squared lower end of the shaft 60 to form a bearing for the latter. The nut 257 is bored out to receive a pressure spring 263 which bears on the upper one of a series of friction discs or washers 264 alternating with washers or discs 265. The washers 264 are bored out to encircle the squared end of the shaft 60 and have oppositely extending projections 266 fitting in vertical grooves 267 in the casing 256 and the washers 265 have square holes in which loosely fits the lower squared end of the shaft 60. It will be seen that the washers 265 rotate with the shaft 60 and that the washers 264 rotate with the casing 256 and that through frictional contact of the washers with each other, caused by the pressure of the spring 263, the movement of the washers 264 is transmitted to the washers 265 on the shaft 60 and the latter is rotated. If the mechanism in the gear housing 64 or parts associated with the carriage should for some reason jam or become inoperative so that they do not function properly the pressure exerted by the spring 263 is so regulated that the washers 265 will slip on the washers 264 without imparting movement to the shaft 60 thus insuring that none of the parts will be injured.

It will now be seen that the above described constructions are well calculated to accomplish the objects primarily stated. At the same time it is to be understood that these constructions are susceptible of considerable modification without departure from the spirit and scope of the invention and consequently in the claims which follow the essential elements are cited without limitation to details of construction.

I claim:

1. In a machine of the class described, the combination of a laterally shiftable carriage, a prime mover, a clutch through which the prime mover shifts said carriage, and means operated by the carriage for rendering said clutch ineffective in certain columnar positions of the carriage.

2. In a machine of the class described, the combination of a laterally shiftable carriage, a prime mover for moving the carriage in only one direction, a clutch through which the prime mover shifts said carriage in said direction, and means carried by the carriage for disconnecting said clutch in different columnar positions of the carriage.

3. In a machine of the class described, the combination of a laterally shiftable carriage, a prime mover, a clutch comprising clutch members one of which is adapted to be

moved into and out of clutching position, and means for moving said clutch member out of clutch position upon movement of the carriage past any one of a plurality of points.

4. In a machine of the class described, the combination of a laterally shiftable carriage, a prime mover, a clutch including a member adapted to be moved into clutching position and through which the prime mover shifts the carriage, and means actuated by movement of the carriage for moving said member out of clutching position upon movement of the carriage past any selected one of a plurality of points.

5. In a machine of the class described, a laterally shiftable carriage, a prime mover, a clutch including two clutch members one of which is adapted to be moved bodily into and out of clutching position, a lever connected to said bodily moved member and means carried by the carriage for rocking the lever to move said bodily moved member out of clutching engagement upon movement of the carriage past any one of a plurality of points.

6. In a machine of the class described, the combination of a laterally shiftable carriage, a prime mover for moving the carriage directly to any one of a plurality of columnar positions by a continuous movement in one direction of the carriage past intermediate columnar positions, means moved to normal position by the carriage to position the carriage in the desired column, and means for moving the aforesaid means out of normal position into position to be operated by the carriage.

7. In a machine of the class described, the combination of a laterally shiftable carriage normally advanced by a step-by-step movement to effect columnar spacing, motor means for automatically returning the carriage to its first columnar position as an incident to the operation of the machine with the carriage in its last columnar position, and means for controlling the return of said carriage by the motor means from one intermediate columnar position directly to a precedent intermediate columnar position predetermined by said controlling means.

8. In a machine of the class described, the combination of a laterally shiftable carriage normally advanced by a step-by-step movement to effect columnar spacing, motor means for automatically returning the carriage to its first columnar position as an incident to the operation of the machine with the carriage in its last columnar position, and means for controlling the return of said carriage by the motor means from any one of a plurality of intermediate columnar positions directly to a precedent intermediate columnar position predetermined by said controlling means.

9. In a machine of the class described, the combination of a laterally shiftable carriage normally advanced by a step-by-step movement to effect columnar spacing, motor means for automatically returning the carriage to its first columnar position as an incident to the operation of the machine with the carriage in its last columnar position, and means for controlling the return of said carriage by the motor means from the last intermediate columnar position directly to a precedent intermediate columnar position predetermined by said controlling means.
10. In a machine of the class described, the combination of a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means for controlling return of said carriage by said second motor means from an advanced columnar position, different from that from which the carriage is normally returned, to a precedent position different from that to which the carriage is normally returned and predetermined by said controlling means.
11. In a machine of the class described, a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position and means for controlling return of the carriage by said second motor means directly by a continuous movement in one direction from an advanced columnar position, different from that from which the carriage is normally returned, to a precedent position different from that to which the carriage is normally returned and predetermined by said controlling means.
12. In a machine of the class described, the combination of a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means for controlling return of said carriage by said second motor means from any one of a plurality of advanced columnar positions to a pre-
- cedent position different from that to which the carriage is normally returned and predetermined by said controlling means.
13. In a machine of the class described, the combination of a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means for controlling return of said carriage by said second motor means from said advanced columnar position to a precedent position different from that to which the carriage is normally returned and predetermined by said controlling means.
14. In a machine of the class described, a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means operated by the carriage for controlling the return of said carriage by said second motor means from an advanced position different from that from which the carriage is normally returned to a precedent position different from that to which the carriage is normally returned.
15. In a machine of the class described, a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means operated by the carriage for controlling the return of said carriage by said second motor means from said advanced columnar position to a precedent position different from that to which the carriage is normally returned.
16. In a machine of the class described, the combination of a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means operated by the carriage for controlling the return of said carriage for controlling the return of said car-

riage by said second motor means directly by a continuous movement in one direction from an advanced columnar position different from that from which the carriage is normally returned to a precedent position different from that to which the carriage is normally returned.

17. In a machine of the class described, the combination of a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, and means operated by the carriage for controlling the return of said carriage by said motor means directly by a continuous movement in one direction from any one of a plurality of advanced columnar positions to a precedent position different from that to which the carriage is normally returned.

18. In a machine of the class described, the combination of a laterally shiftable carriage, provision for normally moving the carriage step-by-step in one direction to effect columnar spacing as an incident to each operation of the machine, motor means and connections therefrom to the carriage for moving the carriage in the opposite direction, and means for automatically disabling said connections at different points of movement of the carriage in the last mentioned direction.

19. In a machine of the class described, the combination of a laterally shiftable carriage adapted to be moved normally step-by-step in one direction to effect columnar spacing as an incident to the operation of the machine, automatic means for controlling said step-by-step movement, motor means and connections from said motor means to the carriage for moving the carriage in the opposite direction, and means for automatically disabling said connections after variable extents of movement of the carriage in the last mentioned direction.

20. In a machine of the class described, the combination of a laterally shiftable carriage adapted to be moved normally in one direction from one columnar position to the next as an incident to each operation of the machine, automatic means for controlling said movement, motor means and connections therefrom to the carriage for moving the carriage in the opposite direction, and means carried by the carriage for disabling said connections at different points of movement of the carriage in the last mentioned direction.

21. In a machine of the class described, the combination of a laterally shiftable car-

riage, a motor for shifting the same, a clutch intermediate the motor and carriage, a member on the carriage for disabling the clutch to position the carriage in a certain position, and a manually positioned device actuated by said member to disable the clutch and position the carriage in another columnar position.

22. In a machine of the class described, the combination of a laterally shiftable carriage, a motor for shifting the same, a clutch intermediate the motor and carriage, a member on the carriage for disabling the clutch to position the carriage in a certain position and a manually positioned device for rendering said clutch effective and actuated by said member to disable the clutch and position the carriage in another columnar position.

23. In a machine of the class described, the combination, a laterally shiftable carriage, a motor for moving the carriage step-by-step in one direction, a second motor for moving the carriage in the opposite direction, means for automatically rendering the second motor effective to move the carriage and for rendering the second motor ineffective to position the carriage in one columnar position, and manual means for rendering the second motor ineffective to position the carriage in another columnar position.

24. In a machine of the class described, the combination of a laterally shiftable carriage, a prime mover for actuating the same, a member carried by the carriage for rendering said prime mover effective to move the carriage, manually operated means for rendering said prime mover effective to move the carriage independently of said member and an element on said carriage for rendering said prime mover ineffective and thereby control the positioning of the carriage in one columnar position and adapted to operate said manually operated means to render the prime mover ineffective and thereby control the positioning of the carriage in a different columnar position.

25. In a machine of the class described, the combination of a laterally shiftable carriage, a prime mover for shifting the same, a clutch between the carriage and prime mover, a member carried by said carriage for rendering the clutch effective to move the carriage, and manually operated means for rendering said clutch effective to move the carriage independently of said member, and an element on said carriage for disabling the clutch, after it has been rendered effective by said member, to position the carriage in one columnar position and also adapted to operate said means to disable said clutch, after it has been rendered effective by the latter, to position the carriage in another columnar position.

26. In a machine of the class described, the combination of a laterally shiftable carriage, a motor for shifting the same, a clutch intermediate the carriage and motor, a lever connected to one member of the clutch, a cam member on said carriage for operating said lever to render the clutch effective, and manually operated means for operating said lever to render the clutch effective independently of said cam member.
27. In a machine of the class described, the combination of a laterally shiftable carriage, a motor for shifting the carriage in one direction by a step-by-step movement, a second motor for shifting the carriage in the opposite direction by a continuous movement, a clutch intermediate the carriage and second motor, a lever connected to one member of the clutch, a cam member on said carriage for automatically operating said lever to render the clutch effective, and manually operated means for operating said clutch to render the clutch effective independently of said cam member.
28. In a machine of the class described, the combination of a laterally shiftable carriage, a motor for shifting the same, a clutch intermediate the carriage and the motor, a lever connected to one member of the clutch, a cam member on said carriage for operating said lever to render the clutch effective, and manually operated means for operating said lever to render the clutch effective independently of said cam member, and means for directly operating said lever to render the clutch ineffective after the same has been rendered effective by said member and for operating said manually operated means to operate the lever and thereby render the clutch ineffective after the lever has been manually operated.
29. In a machine of the class described, the combination of a laterally shiftable carriage, a motor for shifting the carriage in one direction by a step-by-step movement, a second motor for shifting the carriage in the opposite direction by a continuous movement, a clutch intermediate the carriage and the second motor, a lever connected to one member of the clutch, a cam member on said carriage for operating said lever to render the clutch effective, and manually operated means for operating said lever to render the clutch effective independently of said cam member, and means for directly operating said lever to render the clutch ineffective after the lever has been operated by said member and for operating said manually operated means to operate the lever to render the clutch ineffective after the lever has been manually operated.
30. In a machine of the class described, the combination of a laterally shiftable carriage, a motor for shifting the carriage in one direction by a step-by-step movement, a second motor for shifting the carriage in the opposite direction by a continuous movement, a clutch intermediate the carriage and the second motor, a lever connected to one member of the clutch, a cam member on said carriage for automatically operating said lever to render the clutch effective, manually operated means for operating said clutch to render the clutch effective independently of said cam member, and a cam element for directly operating
- second motor for shifting the carriage in the opposite direction by a continuous movement, a clutch intermediate the carriage and second motor, a lever connected to one member of the clutch, a cam member on said carriage for automatically operating said lever to render the clutch effective, means for adjustably mounting the cam member on the carriage, and manually operated means for operating said clutch to render the clutch effective independently of said cam member.
31. In a machine of the class described, the combination of a laterally shiftable carriage, a motor for shifting the carriage in one direction by a step-by-step-movement, a second motor for shifting the carriage in the opposite direction by a continuous movement, a clutch intermediate the carriage and the second motor, a lever connected to one member of the clutch, a cam member on said carriage for automatically operating said lever to render the clutch effective, means for adjustably mounting the cam member on the carriage, manually operated means for operating said clutch to render the clutch effective independently of said cam member, and means for directly operating said lever to render the clutch ineffective after the lever has been operated by said member and for operating said manually operable means to operate the lever and render the clutch ineffective after the lever has been manually operated.
32. In a machine of the class described, the combination of a laterally shiftable carriage, a motor for shifting the same, a clutch intermediate the carriage and motor, a lever connected to one member of the clutch, a cam member on said carriage for operating said lever to render the clutch ineffective, manually operated means for operating said clutch to render the clutch effective independently of said cam member, a cam element on said carriage for directly operating said lever to render the clutch ineffective after the same has been operated by said cam member and for operating said manually operated means to operate the lever and render the clutch ineffective after the lever has been manually operated.
33. In a machine of the class described, the combination of a laterally shiftable carriage, a motor for shifting the carriage in one direction by a step-by-step movement, a second motor for shifting the carriage in the opposite direction by a continuous movement, a clutch intermediate the carriage and the second motor, a lever connected to one member of the clutch, a cam member on said carriage for automatically operating said lever to render the clutch effective, manually operated means for operating said clutch to render the clutch effective independently of said cam member, and a cam element for directly operating

said lever to render the clutch ineffective after the lever has been operated by said cam member and for operating said manually operated means to operate the lever and 5 render the clutch ineffective after the lever has been manually operated.

34. In a machine of the class described, the combination of a laterally shiftable carriage, a motor for shifting the carriage, a 10 clutch intermediate the motor and carriage, a manually operated device for rendering the clutch effective, a member on said device, and a cam element on said carriage for operating said member to render the 15 clutch ineffective.

35. In a machine of the class described, the combination of a laterally shiftable carriage, a motor for shifting the carriage, a 20 clutch intermediate the motor and carriage, a manually operated device for rendering the clutch effective, a member on said device, a cam element on said carriage for operating the member to render the clutch ineffective, and means for adjustably mounting 25 said cam element on the carriage.

36. In a machine of the class described, the combination of a laterally shiftable carriage, a motor for shifting the carriage, a 30 clutch intermediate the motor and carriage, a manually operated device for rendering the clutch effective, a member on said device, a cam element on said carriage for operating the member to render the clutch ineffective, and means for rendering said 35 clutch effective independently of said manually operated means.

37. In a machine of the class described, the combination of a laterally shiftable carriage, a motor for shifting the carriage, a 40 clutch intermediate said motor and the carriage, a manually operated device for rendering the clutch effective, a member on said device, a cam element adjustably mounted on the carriage for operating the member 45 to render the clutch ineffective, and means for rendering said clutch effective independently of said manually operated means.

38. In a machine of the class described, the combination of a laterally shiftable carriage; a motor for shifting the same; a 50 clutch intermediate the carriage and motor comprising two members which are adapted to be coupled, one of the members being provided with projections and the other 55 with slots, a coupling element having projections extending through said slots and a yielding connection between the coupling element and one of said members for insuring proper engagement of the projections 60 on the element and the one member; and means for moving said coupling element into and out of clutch position.

39. In a machine of the class described, the combination of a laterally shiftable carriage, a main operating mechanism for the 65

machine, a prime mover for operating said mechanism and shifting the carriage from one columnar position to another as an incident to the operation of the machine with the carriage in the first mentioned position, 70 and manually operable means for rendering said prime mover effective to shift the carriage from the first mentioned columnar position to a columnar position different than the second mentioned columnar position, 75 without operating the machine.

40. In a machine of the class described, the combination of a laterally shiftable carriage, a main operating mechanism for the machine, a prime mover for operating said 80 mechanism and shifting the carriage from one columnar position to another as an incident to the operation of the machine with the carriage in the first mentioned position, and manually operable means for rendering said prime mover effective to shift the carriage from any one of a plurality of columnar positions to a columnar position different than the second mentioned columnar position, 85 without operating the machine. 90

41. In a machine of the class described, the combination of a laterally shiftable carriage, a main operating mechanism, a prime mover for operating said mechanism, a spring for shifting the carriage in one direction from one columnar position to another, connections operated by the prime mover as an incident to the operation of the machine with the carriage in a certain columnar position to shift the carriage in 100 the opposite direction, and means for rendering said connections effective so that the prime mover will move the carriage in said opposite direction without operating the machine. 105

42. In a machine of the class described, the combination of a laterally shiftable carriage, a main operating mechanism, a prime mover for operating said mechanism, a spring for shifting said carriage for one columnar position to the next upon each operation of the machine, a clutch rendered effective as an incident to the operation of the machine with the carriage in the last columnar position and operated by the prime mover to shift 115 the carriage to its first columnar position and manually operable means controlling the enabling and disabling of said clutch so that the prime mover without operating the machine, shifts the carriage from an advanced columnar position to an intermediate precedent columnar position. 120

43. In a machine of the class described, the combination of a laterally shiftable carriage, a main operating mechanism, a prime mover for operating said mechanism, a spring for shifting said carriage for one columnar position to the next upon each operation of the machine, a clutch rendered effective as 125 an incident to the operation of the machine 130

with the carriage in the last columnar position and operated by the prime mover to shift the carriage to its first columnar position and manually operable means controlling the enabling and disabling of said clutch so that the prime mover without operating the machine, shifts the carriage from any one of a plurality of advanced columnar positions to an intermediate precedent columnar position.

44. In a machine of the class described, the combination of a laterally shiftable carriage, a main operating mechanism, a prime mover for operating said mechanism, a clutch between the carriage and prime mover, means operated by the carriage as an incident to the operation of the machine for rendering the clutch effective and ineffective so that the prime mover shifts the carriage from one columnar position to another and a manually operated device for operating said means and operated thereby to render the clutch effective and ineffective so that the prime mover without operating the machine, shifts the carriage from one columnar position to another, both of which are different than those first mentioned.

45. In a machine of the class described, the combination of a laterally shiftable carriage, a main operating mechanism, a prime mover for operating said mechanism, a clutch between the carriage and prime mover, means operated by the carriage as an incident to the operation of the machine for rendering the clutch effective and ineffective so that the prime mover shifts the carriage from one columnar position to another, and a manually operated device for operating said means and operated thereby to render the clutch effective and ineffective so that the prime mover without operating the machine, shifts the carriage from any one of a plurality of columnar positions to another columnar position different than the columnar position to which it is shifted as an incident to the operation of the machine.

46. In a machine of the class described, the combination of a laterally shiftable carriage, a motor for shifting the carriage, a clutch between the motor and carriage, a member on said carriage for rendering the clutch effective, and a latch for adjusting said member on the carriage and adapted to be operated to release said member when the carriage is moved beyond its normal extent of movement.

47. In a machine of the class described, the combination of a laterally shiftable carriage, a motor for shifting the carriage in one direction automatically by a step-by-step movement from one columnar position to the next and past the last columnar position, a second motor for shifting the carriage in the opposite direction, a clutch

intermediate the second motor and the carriage, and a cam member on the carriage for rendering the clutch effective upon movement of the carriage past the last columnar position by the first motor to cause the second motor to move the carriage in the opposite direction.

48. In a machine of the class described, the combination of a laterally shiftable carriage, a motor for shifting the same in one direction by a step-by-step movement from one columnar position to the next, and past the last columnar position, a second motor for shifting the carriage in the opposite direction, a clutch intermediate the second motor and the carriage, means for rendering the clutch effective upon movement of the carriage past the last columnar position by the first motor to cause the second motor to move the carriage in the opposite direction, and means on said carriage for disabling said clutch to position the carriage in a precedent columnar position.

49. In a machine of the class described, the combination of a laterally shiftable carriage, a spring for shifting the carriage by a step-by-step movement from one columnar position to the next, stop means for controlling the shifting of the carriage by said spring, the carriage being moved past its last columnar position as an incident to the operation of the machine, a motor for moving the carriage in the opposite direction, and means on the carriage for rendering said clutch effective by movement of the carriage past its last columnar position by the spring.

50. In a machine of the class described, the combination of a laterally shiftable carriage, a spring for shifting the carriage by a step-by-step movement from one columnar position to the next, stop means for controlling the shifting of the carriage by said spring, the carriage being moved past its last columnar position as an incident to the operation of the machine, a motor for moving the carriage in the opposite direction, means on the carriage for rendering said clutch effective by movement of the carriage past its last columnar position by the spring, and manually operated means for rendering said clutch effective when the carriage is in a different columnar position.

51. In a machine of the class described, the combination of a laterally shiftable carriage, a spring for shifting the carriage by a step-by-step movement from one columnar position to the next, stop means for controlling the shifting of the carriage by said spring, the carriage being moved past its last columnar position as an incident to the operation of the machine, a motor for moving the carriage in the opposite direction, and a cam member adjustably mounted on the carriage for rendering said clutch effective by move-

ment of the carriage past its last columnar position by the spring.

52. In a machine of the class described, the combination of a laterally shiftable carriage, a spring for shifting the carriage by a step-by-step movement from one columnar position to the next, stop means for controlling the shifting of the carriage by said spring, the carriage being moved past its last columnar position as an incident to the operation of the machine, a motor for moving the carriage in the opposite direction, a cam member adjustably mounted on the carriage for rendering said clutch effective by movement of the carriage past its last columnar position by the spring, and manually operated means for rendering said clutch effective when the carriage is in any one of a plurality of columnar positions.

53. In a machine of the class described, a laterally shiftable carriage, a motor for advancing the carriage from one columnar position to the next advanced columnar position upon each operation of the machine, a second motor means for normally returning the carriage to a certain precedent columnar position as an incident to the operation of the machine with the carriage in a certain advanced columnar position, means for controlling return of said carriage by said second motor means from an advanced columnar position different than that from which the carriage is normally returned to a precedent columnar position different than that to which the carriage is normally returned, and line-spacing mechanism operated by said second motor as an incident to either return movement of the carriage.

54. In a machine of the class described, the combination of a laterally shiftable carriage, a motor for advancing the carriage from one columnar position to the next advanced columnar position upon each operation of the machine, a second motor for normally returning the carriage to a certain precedent columnar position as an incident to the operation of the machine with the carriage in a certain advanced columnar position, means for controlling the return of the carriage by said second motor from an advanced columnar position different than that from which the carriage is normally returned to a precedent position different than that to which the carriage is normally returned, line-spacing mechanism, and a cam member mounted on the carriage and moved relative thereto by said second motor to operate the line-spacing mechanism as an incident to either return movement of the carriage.

55. In a machine of the class described, the combination of a laterally shiftable carriage, a rack bar thereon adapted to be moved relatively to the carriage, a motor and connections to the rack bar for actuating

ing the rack bar and shifting the carriage, the rack bar being moved relative to the carriage preliminarily to the shaft of the carriage, line-spacing mechanism, means on said rack bar for operating the line-spacing mechanism upon said relative preliminary movement of the rack bar, means on said rack bar for disabling said connections and a spring for moving said rack bar to normal position relative to the carriage when said connections are disabled.

56. In a machine of the class described, the combination of a laterally shiftable carriage, a spring for moving the carriage in one direction, a motor for moving the carriage in the opposite direction, connections intermediate the motor and carriage, a device mounted on the carriage and moved with the carriage in the first direction to render said connections effective and then in the opposite direction relative to the carriage to operate the line-spacing mechanism.

57. In a machine of the class described, the combination of a laterally shiftable carriage, a spring for moving the carriage in one direction, a motor for moving the carriage in the opposite direction, connections intermediate the motor and carriage, a device mounted on the carriage and moved with the carriage in the first direction to render said connections effective and then in the opposite direction relative to the carriage to operate the line-spacing mechanism, and means on said device for rendering said connections ineffective.

58. In a machine of the class described, the combination of a laterally shiftable carriage, line-spacing mechanism, a spring for moving the carriage in one direction, a motor for moving the carriage in the opposite direction, a rack bar mounted on the carriage and adapted to be moved relative thereto, a clutch intermediate the motor and rack bar, the rack bar being moved with the carriage by the spring to render said clutch effective and moved relative to the carriage by the motor to operate the line-spacing mechanism.

59. In a machine of the class described, the combination of a laterally shiftable carriage, line-spacing mechanism, a spring for moving the carriage in one direction, a motor for moving the carriage in the opposite direction, a rack bar mounted on the carriage and adapted to have a step of movement relative thereto, a clutch intermediate the motor and rack bar, the rack bar being moved with the carriage by the spring to render said clutch effective and moved relative to the carriage by the motor to operate the line-spacing mechanism, and means on said rack bar for rendering said clutch ineffective.

60. In a machine of the class described, the combination of a laterally shiftable car-

- riage, a spring for moving the carriage in one direction, column stops, a motor for moving the carriage in the opposite direction, a rack bar mounted on the carriage, and
- 5 a clutch intermediate the rack bar and carriage adapted to be moved relative thereto, the rack bar being moved with the carriage by the spring to render the clutch effective and moved relatively to the carriage by the
- 10 motor as a precedent and incident to movement of the carriage by the motor to render the column stops ineffective.
61. In a machine of the class described, the combination of a laterally shiftable carriage, motor means for shifting the carriage from one columnar position to the next advanced columnar position as an incident to the operation of the machine, column stops for controlling such movement of the carriage, means for automatically operating said stops for said purpose, and manual means for controlling operation of said stops to effect movement of the carriage directly from one columnar position to a predetermined advanced columnar position without stopping at an intermediate columnar position.
62. In a machine of the class described, a combination of a laterally shiftable carriage, motor means for shifting the carriage from one columnar position to the next advanced columnar position as an incident to the operation of the machine, stop mechanism controlling such columnar spacing, manually controlled means for latching said mechanism in ineffective position and means carried by the carriage for effecting disablement of said latch means when the carriage is moved to a predetermined position.
- 30 63. In a machine of the class described, the combination of a laterally shiftable carriage, columnar stops for controlling columnar spacing of the carriage, a normally ineffective latch, manual means for controlling movement of the latch into position to latch the stops in ineffective position and means on the carriage for effecting disablement of the latch.
- 35 64. In a machine of the class described, the combination of a laterally shiftable carriage, columnar stops for controlling columnar shifting of the carriage, means operated as an incident to the operation of the machine for rocking said stops into and out of effective position, manually controlled means for temporarily delaying movement of the stops into effective position and automatic means for disabling said manually controlled means.
- 40 65. In a machine of the class described, the combination of a laterally shiftable carriage, columnar stops for controlling columnar shifting of the carriage, a latch for retaining the column stops out of effective position, a bail on the carriage, manually con-
- trolled means cooperating with the bail to normally retain the latch in inoperative condition and means for disabling the latch after it has been rendered effective.
66. In a machine of the class described, the combination of a laterally shiftable carriage, columnar stops for controlling columnar spacing of the carriage, a latch for retaining the columnar stops out of effective position, a bail on the carriage, manually controlled means cooperating with the bail to normally retain the latch in inoperative condition, means for holding said manually controlled means in moved position and a device for disabling said holding means.
- 70 67. In a machine of the class described, the combination of a laterally shiftable carriage, columnar stops for controlling columnar shifting of the carriage, a latch for retaining the columnar stops out of effective position, a bail on the carriage, manually controlled means cooperating with the bail to normally retain the latch in inoperative condition, a spring adapted to move the latch out of latching position and means for giving the bail an excessive movement to insure movement of the latch out of latching position.
- 75 68. In a machine of the class described, the combination of a laterally shiftable carriage, means for controlling columnar spacing, a motor and a member on the carriage driven by the motor to shift the carriage, the member being given an initial movement relative to the carriage to disable said means during movement of the carriage in one direction by said motor.
- 80 69. In a machine of the class described, the combination of a laterally shiftable carriage, mechanism for controlling columnar spacing in one direction, a motor, a member on the carriage driven by the motor to move the carriage in the opposite direction, a cam on said member, and connections operated by said cam to disable said mechanism during movement of the carriage in the last mentioned direction.
- 85 70. In a machine of the class described, the combination of a laterally shiftable carriage, a spring for moving the carriage in one direction, mechanism for controlling columnar spacing, a rack bar on the carriage, and a motor for moving the rack bar to return the carriage in the opposite direction, the rack bar being given a movement relative to the carriage to disable said controlling mechanism.
- 90 71. In a machine of the class described, a combination of a laterally shiftable carriage, a spring for moving the carriage in one direction, mechanism for controlling columnar spacing, a rack bar on the carriage, a motor for moving the rack bar to return the carriage in the opposite direction, the rack bar being given a movement rela-
- 95 100 105 110 115 120 125 130

5 tive to the carriage to disable the controlling mechanism, line spacing mechanism and means on the rack bar for operating the line spacing mechanism when the rack bar is given said movement relative to the carriage.

72. In a machine of the class described, the combination of a laterally shiftable carriage, means for controlling columnar spacing, a motor, a member on the carriage driven by the motor to return the carriage in one direction, the member being given an initial movement relative to the carriage to disable said mechanism during return movement of 10 the carriage, line spacing mechanism and means on said member for operating said line spacing mechanism upon movement of 15 said member relative to the carriage.

73. In a machine of the class described, 20 a combination of a laterally shiftable carriage, a mechanism for controlling columnar spacing of the carriage, a motor for returning the carriage in one direction, a member on said carriage driven by the motor 25 to return the carriage, the member being given a step of movement relative to the carriage, a clutch intermediate the member and motor, a line spacing mechanism, an element on said member for enabling said 30 clutch and a device on said member for disabling said controlling mechanism and operating the line spacing mechanism upon movement of said member relative to the carriage.

74. In a machine of the class described, 35 the combination of a laterally shiftable carriage, a spring for moving the carriage in one direction a motor for moving the carriage in the opposite direction, means for regulating the speed of movement of the carriage by said spring, and means operated by said motor for automatically disabling 40 said regulating means.

75. In a machine of the class described,

the combination of a laterally shiftable carriage, a spring for moving the carriage in one direction, a motor for moving the carriage in the opposite direction, means including centrifugal weights for retarding movement of the carriage by the spring, and 45 means for moving the weights to ineffective position when the carriage is moved by the motor.

76. In a machine of the class described, 50 the combination of a laterally shiftable carriage, a spring for moving the carriage in one direction, a motor for moving the carriage in the opposite direction, centrifugal weights, and a member rotated in one direction by said spring so that the weights 55 retard movement of the carriage and rotated in the opposite direction by the motor to render the weights ineffective.

77. In a machine of the class described, 60 the combination of a laterally shiftable carriage adapted to be moved in both directions centrifugal weights, and a member rotated in one direction upon movement of the carriage in one direction to retard movement 65 of the carriage, the member being rotated in the opposite direction when the carriage is moved in the other direction to render the weights ineffective.

78. In a machine of the class described, 70 the combination of a laterally shiftable carriage, a spring for moving the carriage in one direction, gearing moved by the carriage when moved by said spring, a motor for operating said gearing to move the carriage in the opposite direction, a clutch for 75 coupling said motor to said gearing, and a governor operated by said gearing for regulating the speed of carriage when moved by said spring, the governor being rendered 80 ineffective when the carriage is moved by 85 the motor.

FRANK C. RINSCHE.
